Primary Examiner — Karen S Acker(74) *Attorney, Agent, or Firm* — Finnegan, Henderson, Farabow, Garrett & Dunner, LLP(57) **CLAIM**

The ornamental design for product packaging, as shown and described.

DESCRIPTION

FIG. 1 is a front view of product packaging showing my new design; and,

FIG. 2 is a perspective view thereof.

The broken lines formed by segments of equal length depict the claimed pre-weakened fold lines of the product packaging. The dot-dash-dot broken lines at the top and bottom of the design form the boundaries of the product packaging and form no part thereof.
